(57) **CLAIM**

The ornamental design for a table, as shown and described.

DESCRIPTION

FIG. 1 is a front right perspective view of a first embodiment of a table showing my new design;

FIG. 2 is a top plan view thereof;

FIG. 3 is a front elevation view thereof, the rear elevation view being a mirror image;

FIG. 4 is a right side elevation view thereof, the left side elevation view being a mirror image;

FIG. 5 is a front right perspective view of a second embodiment of a table showing my new design;

FIG. 6 is a top plan view thereof;

FIG. 7 is a front elevation view thereof, the rear elevation view being a mirror image;

FIG. 8 is a right side elevation view thereof, the left side elevation view being a mirror image;

FIG. 9 is a front right perspective view of a third embodiment of a table showing my new design;

FIG. 10 is a top plan view thereof;

FIG. 11 is a front elevation view thereof, the rear elevation view being a mirror image;

FIG. 12 is a right side elevation view thereof, the left side elevation view being a mirror image;

FIG. 13 is a front right perspective view of a fourth embodiment of a table showing my new design;

FIG. 14 is a top plan view thereof;

FIG. 15 is a front elevation view thereof, the rear elevation view being a mirror image;

FIG. 16 is a right side elevation view thereof, the left side elevation view being a mirror image;

FIG. 17 is a front right perspective view of a fifth embodiment of a table showing my new design;

FIG. 18 is a top plan view thereof;

FIG. 19 is a front elevation view thereof; and,

FIG. 20 is a right side elevation view thereof, the left side elevation view being a mirror image.

(Continued)

The second through fifth embodiments are shown with symbolic break lines and those portions of the article between the break lines form no part of the claimed design. The bottom of the table is not shown in the drawings or described in the specification. It is understood that the appearance of any part of the article not shown in the drawings or described in the specification forms no part of the claimed design.

1 Claim, 18 Drawing Sheets
